COPY MACHINE

Kim Yamasaki, Lombard, Ill., assignor to Speed-O-Print Corporation, Chicago, Ill., a corporation of Illinois

Filed Sept. 16, 1959, Ser. No. 57,579

Term of patent 14 years

(Cl. D64—11)

FIG. 1

FIG. 2

Fig. 1 is a front elevational view of the copy machine embodying my new design;

Fig. 2 is a top plan view thereof;

Fig. 3 is a rear elevational view; and

Fig. 4 is an end elevational view thereof as seen from the right-hand end of Fig. 1.

I claim:

The ornamental design for a copy machine, substantially as shown.
